UNITED STATES PATENT OFFICE.

HERMAN A. DEKNATEL, OF NEW YORK, N. Y.

DESIGN FOR A BOX.

SPECIFICATION forming part of Design No. 26,400, dated December 15, 1896.

Application filed May 14, 1896. Serial No. 588,646. Term of patent 3½ years.

To all whom it may concern:

Be it known that I, HERMAN A. DEKNATEL, a citizen of the United States, and a resident of New York, county and State of New York, 5 have invented a new and useful Design for Paper, Metallic, or Wooden Boxes, of which the following is a specification.

The distinctive feature of my design is a box having a round bottom, sloping sides, 10 and a square top.

In the accompanying drawings, Figure 1 shows the box from the top with its tie-ribbon. Fig. 2 gives the appearance when looking at the bottom, and Fig. 3 shows side elevation of the same.

The sides and top may be ornamented with any design or left plain, as such ornamentation forms no part of my design patent.

What I claim and desire to secure by Letters Patent, is—

The design for a box, as herein shown and described.

In testimony that I claim the foregoing as my invention I have signed my name, in presence of two witnesses, this 14th day of April, 25 1896.

HERMAN A. DEKNATEL.

Witnesses:

PETER P. ACRITETTIN,
ADAM FRANK.
